(57) **CLAIM**

The ornamental design for a display frame, as shown and described.

DESCRIPTION

FIG. 1 is a perspective view of a display frame showing our new design;

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is an exploded view thereof, with a frame portion selectively disengaged from a base portion of our display frame;

FIG. 9 is a bottom perspective view of the frame portion; FIG. 10 is a further perspective view showing our display frame removably engaged with further units of our display frame; and,

FIG. 11 is a further perspective view showing our display frame removably engaged with a further frame portion.

The broken lines shown are included only for the purpose of illustrating unclaimed portions of the article and environmental subject matter, and form no part of the claimed design.

1 Claim, 5 Drawing Sheets
